UNITED STATES PATENT OFFICE.

EDWARD G. LEE, OF BROOKLYN, PENNSYLVANIA.

WAGON-SPRING.

SPECIFICATION forming part of Letters Patent No. 375,941, dated January 3, 1888.

Application filed July 2, 1887. Serial No. 243,246. (No model.)

To all whom it may concern:

Be it known that I, EDWARD G. LEE, a citizen of the United States, residing in Brooklyn, in the county of Susquehanna, in the State 5 of Pennsylvania, have invented new and useful Improvements in Wagon-Springs, of which the following is a description.

The invention relates particularly to that class of two-horse wheeled vehicles which are 10 popularly known as "lumber-wagons" or as "farm-wagons;" but it is well adapted for application in other classes of wagons also.

The invention consists in certain novel parts or combinations of parts in connection with a 15 bolster for a wagon, whereby the "body" or box of such wagon, together with its contents, is spring-supported by effective and durable means and at small cost.

In the drawings, Figure 1 is a top plan view 20 of so much of a wagon-bolster and its connections as is necessary to illustrate my invention. Fig. 2 is a transverse vertical section on the line *w w* of Fig. 1. Fig. 3 is an end view showing a slightly-modified construction.

Fig. 4 represents, on an enlarged scale, a longitudinal vertical section on the line *x x* of Fig. 1. Fig. 5 is a transverse section representing a modification in the construction of the body-bars and in the friction-plate upon 30 the same.

A is the bolster, and *a* is one of the two oppositely-placed standards or side stakes thereof.

B B are the body-bars or floor-rests parallel with the bolster and above the plane of the same, as shown. The bars or rests have near each end a top recess, *b*, and they are firmly connected and maintained in parallelism by the connecting-plate *C*, which is let into the 35 bars, so that the upper surface of both and the heads of the securing-screws *c c* are in the same horizontal plane. The supporting-brackets *A'* upon the bolster *A*, oppositely placed, as seen, and secured by through-bolts *a'*, have 40 each a vertical perforation to receive the lower end of the spiral supporting-spring *D*, which is threaded to receive the securing-nut *d'*. The upper end of the spring, similarly threaded, passing through the friction-plate *B'*, extends 45 into the recess *b* in the body-bar, where it is engaged and secured by the nut *d*.

In some cases it may be desirable to con-

nect the upper extremities of the brackets by a web or continuous bearing, as represented in Fig. 3, and it may also sometimes be advantageous to employ a bottom plate, *A*², as in the same figure. When this plate is employed, it will be received within a transverse recess in the bottom of the bolster, and it will be seen that if it be used in connection with a 55 one-part or double bracket the bracket will be held against displacement longitudinally of the bolster, or otherwise, independently of the use of securing-bolts, it being understood that the springs will be formed, by preference, of 60 half-inch rods, and that the nuts *d* and *d'* will have a rigid and firm bearing. The friction-plate *B'* will be attached to the lower face of the body-bars by screws if the plate be made unflanged; but if the plate be formed, as seen 65 in Fig. 5, with an upward and inturned flange, *b'*, to engage the longitudinal groove *b*² in the side of the bar, it may be slipped over the end of the same. Under this latter construction the necessity for securing-screws is avoided, 70 and the plate is held against longitudinal displacement by the straight-threaded extremity *d*² of the spring *D*. The friction-plate will, as is obvious, effectually prevent abrasion of the body-rests, and being, by preference, composed of chilled cast-iron it will be both durable 75 and inexpensive. It will be seen that as thus constructed the springs require no side supports, coupling-rods, guides, flanges, cups, or other extraneous restricting devices of any kind, and 80 that through the provision of the top recesses in the body-bars the upper holding-nut upon the top end of the spring is secured against rotation, and the surface of such bars is left unobstructed and presents a plain surface for 85 the reception of the wagon-box.

Having described my invention, I claim—

1. A wagon-bolster which is provided with vertically-perforated brackets, body-bars which are provided with vertical perforations 90 and rectangular top recesses, securing-nuts which are adapted to fit the top recesses, and spiral springs which by their upper ends engage the nuts in such top recesses, and which by their lower ends extend through the perforations in the brackets, and are secured by a nut which is applied directly to such lower end, substantially as shown and described.

2. A wagon-bolster which is provided with

- lateral brackets, an end - perforated bottom plate which is received in a transverse recess in the body of the bolster and which is coincident with the horizontal portions of the bracket, connected body-bars which are provided with bottom friction-plates, top recesses, and a securing-nut which is held against rotation by the walls of such recesses, and end-threaded spiral springs, each of which at the top engages the nut in the recess and by its lower extremity extends through both the bracket and the transverse bottom plate and is secured by a nut applied thereon, all in combination, substantially as described.
- 15 3. A wagon-bolster which is provided with lateral brackets, body-bars which are provided with bottom friction plates, which engage a recess or groove formed in each edge of such body-bars, and which are provided, also, with top recesses and with securing - nuts fitted within such recesses, and spiral springs which engage the nuts within the top recesses and which extend through the lateral brackets and

are engaged by a nut beneath the same, all in combination, substantially as set forth.

25

4. The combination, with the bolster A, having perforated brackets A', of the connected body-bars B B, having top recesses, as described, and the springs D D, resting upon and secured to the brackets A' and secured at 30 top to the body-bars, the securing-nut resting in the recess b' of such bars and being applied directly to the threaded end of the spring, substantially as and for the purposes specified.

5. The combination of the bolster A, having perforated side brackets, A', the body-bars having connecting-plate C, top recesses, and bottom guard or friction-plate, B', and the supporting-springs D, secured by nuts applied to the ends thereof, as described, both to the 35 side brackets and to the recessed body-bars, substantially as shown and set forth.
